ATTY'S

United States Patent Office.

IRA YEAMANS, OF BROOKLYN, NEW YORK.

Letters Patent No. 91,696, dated June 22, 1869.

COFFEE-POT.

The Schedule referred to in these Letters Patent and making part of the same.

To all whom it may concern:

Be it known that I, IRA YEAMANS, of the city of Brooklyn, in the county of Kings, and State of New York, have invented a new and useful Improvement in Coffee-Pots; and I do hereby declare that the following is a full, clear, and exact description thereof, which will enable others skilled in the art to make and use the same; reference being had to the accompanying drawing, forming part of this specification.

This invention relates to improvements in coffee-pots, teapots, and other similar vessels for table use, employed for holding liquids to be poured into drinking-cups, and is designed to so arrange them as to avoid the necessity of raising or turning them, as required in the use of these vessels as now constructed.

The invention consists in mounting such vessels on trunnions for turning in a vertical plane, the said trunnion-supports being also capable of revolving in a horizontal plane.

The drawing represents an elevation, partly in section, of a coffee or teapot, arranged according to my improvement.

Similar letters of reference indicate corresponding parts.

I provide a stand, A, preferably of metal, and of any preferred form or design, having in its vertical axis a step B, for a spindle, C, of a horizontal turn-table, E, having two brackets, F, rising from opposite sides, and provided with horizontal bearings, for mounting the trunnions G, of the coffee-pots or other vessels H, so

as to permit them to turn freely, both horizontally and vertically, for pouring, whereby the labor of lifting and holding the said vessels while pouring is saved.

To arrest the movement of the vessels at the right point, in returning to the normal position, and prevent continuous swinging, I provide stops I, near the bottom, at the rear, to strike the top of the turn-table; and to lessen the effect of the concussion, I provide springs K, of India rubber or other substance, either on the stops or on the turn-table.

My improvements are applicable to all such vessels as are used for holding liquids to be poured in small quantities and frequently.

Instead of securing the trunnions in their bearings, by caps L and pins M, as represented in the drawings, I may, if preferred, dispense with them, leaving the trunnions free to permit the vessels to be lifted off or on freely.

Having thus described my invention,

What I claim as new, and desire to secure by Letters Patent, is—

Coffee-pots and other similar vessels, suspended on horizontal turn-tables, and vertically-oscillating trunnions, substantially as specified.

The above specification signed by me, this 16th day of March, 1869.

IRA YEAMANS.
